UNITED STATES PATENT OFFICE.

OSCAR V. BLAZIER, OF GILLETTE, NEW JERSEY, ASSIGNOR OF ONE-HALF
TO WILLIAM A. WOODRUFF, OF PLAINFIELD, NEW JERSEY.

BOTTLE.

SPECIFICATION forming part of Letters Patent No. 603,019, dated April 26, 1898.

Application filed February 15, 1897. Serial No. 623,370. (No model.)

To all whom it may concern:

Be it known that I, OSCAR V. BLAZIER, a citizen of the United States, residing at Gillette, in the county of Morris and State of New Jersey, have invented an Improvement in Bottles, of which the following is a specification.

Bottles are manufactured extensively of peculiar sizes or shapes, and names are often made on the glass, and bottles of this character are employed for holding fluids, especially proprietary medicines and liquids of general consumption, and in many instances these bottles are gathered up and employed by unscrupulous persons who refill them with a liquid approximating the original and sell them as of the original make, thus defrauding the parties originally using the bottles and frequently placing an inferior article upon the market.

20 Numerous appliances have been made seeking to prevent the refilling of the bottle; but these are often costly and inefficient in preventing the surreptitious use of such bottles.

The object of the present invention is to 25 make it to the advantage of the purchaser or user of the contents of the bottle to break the glass of the bottle, and thus destroy its utility and prevent the same being refilled; and with this object in view I insert into the glass of 30 the bottle a coupon-holder that cannot be detached except by breaking the glass, and within this holder there is a coupon representing a money value payable by the original filler of the bottle, so that upon forward- 35 ing such coupons, pursuant to the directions on the bottle, the party will be entitled to a money consideration.

In the drawings, Figure 1 represents a bottle partially in section, and Fig. 2 shows the 40 parts of the coupon-holder and a coupon separated.

It is to be understood that the bottle A is to be of any desired size or character, and usually it will be what is termed a "proprietary" bottle having the name of the user or other marks and numbers referring to the contents of the bottle, and as these bottles

are usually labeled it is advantageous to introduce upon such labels statements or directions concerning the coupon, the value of the 50 same, and the party to whom coupons are to be forwarded.

The coupon-holder B is to be made of a size and shape adapted to receive the coupon 2. This is advantageously of metal and may be 55 stamped with a number, name, or other device indicative of origin and adapted to prevent fraudulent reproduction, and this coupon is received into the holder and placed in the mold employed for receiving the glass of 60 which the bottle is composed, so that in blowing or molding the bottle the coupon-holder is sufficiently surrounded upon its edges to prevent the same being separated from the bottle without breaking the glass. 65

I find it convenient to make the holder of two parts, with beveled edges, so that the holder may be dropped into the mold with the coupon in it, and the glass at the bottom of the bottle will be forced around the edges of 70 the coupon-holder. I have shown one part of the coupon-holder as formed with a central circular projection receiving a short tubular cap 4, the coupon 2 being introduced between the parts 3 and 4 before they are closed together. 75

I do not confine myself to any particular size or shape of coupon-holder, as the same may vary according to the character of the coupon and to the bottle with which the same 80 is to be applied.

I claim as my invention—

The coupon-holder having beveled edges and a central circular projection and a tubular cap fitting such projection, and a coupon 85 held between the parts, and the holder secured in the bottle by the glass around the beveled edges, substantially as specified.

Signed by me this 16th day of January, 1897.

OSCAR V. BLAZIER.
